UNITED STATES PATENT OFFICE.

JOHN L. WILSON, OF EVERETT, MASSACHUSETTS, ASSIGNOR TO STEEL CABLE ENGINEERING COMPANY, OF BOSTON, MASSACHUSETTS, A CORPORATION OF MAINE.

CONVEYER-LOADING DEVICE.

No. 875,307.

Specification of Letters Patent.

Patented Dec. 31, 1907.

Application filed March 16, 1907. Serial No. 362,628.

To all whom it may concern:

Be it known that I, JOHN L. WILSON, a citizen of the United States, residing in Everett, in the county of Middlesex and State of Massachusetts, have invented an Improvement in Conveyer-Loading Devices, of which the following description, in connection with the accompanying drawings, is a specification, like letters on the drawings representing like parts.

My invention relates to loading devices and particularly, though not exclusively, to those employed in loading conveyers and wherein a hopper or bin in which material is stored is provided with a chute and gate for controlling the amount of material delivered to the conveyer.

My invention aims generally to improve devices of this type by providing a gate of novel construction and simple and effective means for operating the same. The above, however, together with other novel features and objects of my invention, will be best understood and appreciated from the following description and accompanying drawings of a conveyer apparatus and loading device embodying one form of my invention and selected for purposes of illustration, its scope being more particularly pointed out in the appended claims.

In the drawings; Figure 1, is a side elevation with parts broken away, of a selected embodiment of my invention showing the adjacent portions of a loading device and conveyer. Fig. 2, a plan view of the same, to show the chute, its controlling gate, and the adjacent portions of the conveyer below it; Fig. 3, a transverse vertical section, from the right, on line 3—3, Fig. 1; Fig. 4, a detail in left side elevation and on a somewhat larger scale, showing the loading device with its gate closed and about to be opened by the movement of the conveyer in presenting a bucket in loading position below it; and, Fig. 5, a similar detail, with parts broken away, to show the gate opened and in the position in which it is maintained while loading one of the buckets.

Referring to the drawings and to the particular embodiment of my invention herein selected for purposes of illustration, 1 represents the bottom portion of a bin or hopper, B, in which the material to be loaded is stored. This bin or hopper may obviously

be of any usual or desired construction, but as herein shown, (Figs. 1 and 4) is provided with the usual inclined walls 2, which direct the contained material toward the orifice in the bottom of the hopper and into a preferably inclined chute 3, secured, in any suitable manner, to the bottom of the hopper. This chute directs the flow or run of the material received from the hopper, into or upon the conveyer, C, arranged below it. This conveyer may be of any suitable or desired type, one of preferred construction being hereinafter more particularly described. As here shown, however, it is preferably provided with a plurality of conveying elements, for example, buckets, 4, which are to be successively loaded as they are moved to and from loading position relative to the chute 3 by the movements of said conveyer. As usual with hoppers and chutes of this type, the open end or mouth of the chute is provided with a suitable closing device for normally arresting the flow of material. In the present instance, I preferably provide for this purpose, an oscillatory gate, 5, of general U shape, having its normally vertical or upturned arms, 5^a, pivotally and exteriorly mounted, as at 6 (Figs. 1 and 4), to the vertical sides or end walls of the chute and preferably at one side and in rear of the center line thereof.

With the gate closed the entire weight of the material in the chute and that of the superincumbent mass resting thereon rests upon the closing member of the gate, 5, and exerts more or less pressure thereon, so that to move the same forwardly to open, or rearwardly to close it, said movements are resisted by the friction produced by the material which rests upon it. Various types of gates and closing devices have been employed or proposed for closing the mouth of the chute and for controlling the movement of material therethrough, but of these the sliding gate is the least disadvantageous but is nevertheless objectionable in that considerable force is required to overcome said friction and to close the gate and much more than is required in my device, which is a feature of considerable importance, inasmuch as when it is desired to arrest the flow of material, the gate should be closed rapidly. To secure such movement, I provide suitable means for diminishing the friction between

the mass of material within the chute and the closing member of the gate, 5, and I also provide means for increasing the moment and thereby the velocity of closure.

5 As herein shown, the walls of the chute, 3, are provided with bottom edges, 7, (dotted lines, Fig. 4) which are concentric with the pivot, 6, of said gate, and the closing member of the latter is eccentric therewith, as 10 best shown in Figs. 1 and 4, the upper and outer portion of said closing member receding from the upper front and adjacent end of the chute, while the lower and rear portion or edge of said gate is substantially tangent 15 to the curved ends, 7, of the chute sides, as at 8, (Fig. 4). If this gate were provided with a closing member concentric to the pivots, 6, thereof and hence adapted to slide upon and over said curvilinear ends, 7, of the chute, 20 upon closing the gate, there would be a continual increase in friction between said closing member and the mass of the material in the chute arrested thereby. With such construction, it is evident that the frictional 25 area, the amount of friction, and hence the force required to produce such closing movement of the gate will increase as the gate is moved from its open towards its closed position owing to the increasing area of the 30 closing member presented to and to arrest the flow of material within the chute. By my construction, however, only the rear portion of the closing member, the left, Figs. 4 and 5, slides rearwardly and concentrically 35 over the concentric ends of the chute to cut off and arrest the flow of material by the closing movement of the gate. During this closing movement the front portion of this closing member, as it moves rearwardly, re- 40 cedes from the said concentric ends of the chute over which the closing edge, 9, Fig. 5, of the gate has just passed, permitting the confined material still to flow a limited distance in the direction in which it was moving 45 and until again arrested by the receding or eccentric portion of the gate. Nearly all of the friction which retards the closing of the gate is produced between said closing edge, 9, and the material arrested thereby. This 50 construction therefore greatly diminishes the amount of friction relative to constructions in which gates are provided with concentric closing members, where the amount of force required to close the gate is much greater 55 and increases with the closing of the gate. Furthermore by providing a gate having an eccentric closing member, the movement of the flowing material as it falls upon said eccentric portion and is arrested thereby, im- 60 parts additional momentum and hence velocity of closure due to the increase in the moment of force and by which the gate is automatically closed. The closing move- 65 ment of the gate is thus rapidly effected until the closing end, 9, strikes the bottom or

stop member 10, (Fig. 5,) of the rear wall of the chute. In moving in the reverse direction or opening the gate and as the rear portions, 9, of the closing member, which is more nearly concentric with the curved chute 70 ends, move forward, the material in front of it is lifted and thrown rearward toward the opening formed by the opening movement of said gate, thereby dislodging the packed material within the chute and setting it in 75 motion for loading the conveyer. While this gate may obviously be operated by any suitable means, hand or otherwise, in the present embodiment of my invention, I preferably provide means for automatically controlling it by and with the movements of the conveyer or the buckets or conveying elements carried thereby. As here shown, (see Figs. 2 and 3), the angular arms 5^a of the gate are pivotally and adjustably connected 80 by links 11 with horizontal operating levers 12, pivotally mounted at their rear ends upon a horizontal supporting shaft 12^a supported at its opposite ends in vertical brackets 13, at the sides of the conveyer. These levers are adjustably and pivotally connected with the lower ends of the links 11, here shown as by slot and screw arrangement represented at 14, (Figs. 4 and 5), the front ends of said levers being also adjustably mounted on said 85 shaft 12^a, so that said ends may be moved vertically relative to their fulcrum or pivot shaft 12^a. As here shown, the fulcrum end of each lever is provided with a vertical slot 15, to receive a bushing 16, by which it is 90 fulcrumed on said shaft 12^a, adjusting bolts 17, being provided for adjusting and securing the bushing at desired elevation. As will presently be shown, these adjustments provide suitable means for varying the times of 95 opening and closing the gate and hence the amount of material loaded into each bucket. The bottom edges of these levers are curved to form wedge or cam surfaces, 12', 12'' and are provided with leather pads, 18, adapted 100 to bear upon and be engaged by a part of the movable conveyer for swinging the same about their fulcrum 12^a. As will presently be more particularly described, the swinging movements of these levers raise and lower 105 their front ends to move said links and thereby open and close said gate, the closing movement of the gate and the downward swing of the connected levers being produced 110 obviously by the force of gravity acting 115 thereon and by the weight of material arrested by the gate.

In order that the loading device may be controlled by the movements of the conveyer, the latter is provided with members 125 to coöperate with the leather protected faces of said levers to cause periodical elevation and permit depression thereof. Obviously, any desired or usual construction of conveyer may be used so long as elements are 130

provided to coöperate with and to actuate said levers, but I preferably provide a conveyer of the type herein shown, comprising a plurality of chains, 20, Fig. 3, between which the buckets 4 are preferably centrally hung for free swinging movement. These chains are composed of a plurality of links, 21, (Figs. 4 and 5), pivotally connected together by a plurality of long pins, 22, (Figs. 10 2 and 3), and short pins, 23, said long and short pins being alternately arranged, the long pins extending across the conveyer for connecting the chains at the sides of the conveyer together and, in the present instance, 15 also providing operating members to coöperate with the levers 12 for automatically governing and moving the gate of the loading device. The chains at the sides of the conveyer are each double and parallel, between which and removably journaled on 20 said long and short pins, are wheels, 24, adapted to run on tracks 25, as the conveyer is positively driven when operating the same. These tracks may be supported in any suitable 25 manner and form part of a conveyer system of any well known commercial type such, for example, as that shown in the patent to Decker, 630,801, to which reference may be made for a more detailed description 30 than is given here. Pivottally mounted on the short studs or pins, 23, are hangers, 26, provided with suitable studs, 27, (Fig. 4), at their lower ends, upon which said buckets, 4, are hung. The tops of these buckets are, in 35 the present instance, preferably rectangular in cross section, their length being approximately equal to that between the long pins and their breadth somewhat wider than the width of the chute, 3, and said gate, 5, so that 40 when the latter is opened, the bucket or buckets will catch all the material which flows from the chute.

Referring now to Figs. 2 and 3, the construction and arrangement described is such 45 that the conveyer and said levers 12 and links 11 pivoted to the ends of said chute, are adapted to oscillate between the vertical sides or walls 28 of the buckets 4, in which position the leathered cam faces of said levers 50 are actuated by the long pins 22, as the conveyer with its buckets moves under the loading device.

Referring to Figs. 4 and 5, the rear cam surfaces 12' incline downwardly and forwardly, so that when the conveyer moves 55 forward the levers, which are successively or periodically engaged by the long pins 22, will first be elevated by the horizontal and forward movement of said pins. These cam surfaces are relatively long to produce a 60 gradual opening of the gate. The cam surfaces 12" however, turn up more abruptly so that as said pins 22 move thereunder, the levers may swing down rapidly to close the 65 gate.

In the present embodiment of my invention, the conveyer herein shown is of a commercial gravity bucket type adapted and employed for loading and unloading coal. This conveyer has a movement from left to 70 right, (Figs. 1, 4 and 5), represented by the arrow on said figures. Referring to Fig. 4, the conveyer is shown as moving to a position to present one of the buckets 4 below the mouth of the chute 3, the long pin 22 at 75 the left of said bucket, bearing upon the long leathered cam faces 12' of said levers 12 and about to elevate the same to open the chute gate upon further movement of the conveyer towards the right. In Fig. 5, the gate has 80 been opened as the conveyer and said bucket 4 have moved farther to the right to position the bucket to receive a load of material released by the opening of the gate. In this position, it will be noted that the long pin, 85 22, has advanced and has by the action of said levers, opened the gate to its fullest extent. Further movement of said conveyer moves the long pin 22 further to the right and permits the more abruptly turned wedge 90 or cam faces 12" of said levers to fall again, but more quickly than when elevated. This closing movement of the gate is effected by the combined action of the weight of the said levers, links, and gate, the weight of the 95 arrested material engaging said gate, and particularly by the eccentric arrangement of the closing member of said gate.

By the adjustments provided for the opposite ends of said levers 12, relative to their 100 fulcrum on the supporting shaft 12^a or to their linked connection with said gate, the time at which the long pins 22 will operate on said levers to open the gate or permit its rapid closure, may be varied to suit the conditions or requirements of the work, it being obvious that as the front or rear ends are lowered, the gate may be opened earlier and when raised the time of opening may be delayed.

In operation, assuming the conveyer to be in motion, as the long pin 22 in rear of one of the buckets, referring to the direction of motion of said conveyer, is moved into position to engage the leathered cam faces of said 115 levers 12, the latter are first elevated to raise the links and swing the gate forward about its pivot 6, to open said gate immediately as the bucket in front of said pin is simultaneously moved into loading position relative to 120 the mouth of the chute. This gate will remain open until said pin moves forward to the position indicated in Fig. 5, when further forward movement will permit the upwardly curved and gate-connected ends of said levers to fall to effect closure of said gate.

The movement of the conveyer being substantially uniform, the gate remains open a predetermined time, consequently a predetermined amount or volume of material will 130

pass through the chute into the bucket below it, the amount of load for each bucket or the weight of material therein, being the same.

By my invention, I have provided very simple and effective means for effecting a rapid closure of the loading device and with a minimum amount of friction and preferably automatically and also adjustable means for regulating the weight or amount of load.

While in the present embodiment of my invention I have described the same with reference to a specific type of conveyer, and with preferred operating means for automatically controlling the same, obviously my invention is not limited thereto, nor to the specific details of construction and arrangement herein selected for purposes of illustration only, it being understood that the same may be modified within wide limits without departing from the spirit and scope thereof.

1. In a device of the type described, conveying means comprising a plurality of material carriers, a loading device therefor, provided with a gate and adjustable lever means arranged in the path of and operated by said conveying means to open and close said gate and for regulating the time of opening and closing.

2. In a device of the type described, a loading device comprising a bin or hopper provided with a delivery chute, a gate for closing and opening the same and normally maintained closed by the material within said chute and provided with a closing member provided with means for reducing the friction of closing.

3. In a device of the type described, a loading device comprising a bin or hopper provided with a delivery chute, a gate for closing and opening the same normally maintained closed by the material within said chute and provided with a closing member adapted upon closing said gate to present a portion thereof in receding relation to the adjacent portion of said chute.

4. In a device of the type described, a loading device provided with a chute and a gate pivoted to said chute having a closing member tangentially eccentric relative to the bottom of said chute.

5. In a device of the type described, a hopper provided with a chute, an oscillatory gate for opening and closing the latter, a lever having a cam face an adjustable link connected with said gate and with said lever and a conveyer provided with coöperating members to engage the cam face of said lever for operating said gate.

6. In a device of the type described, a conveyer provided with a plurality of conveying elements or buckets, a pair of levers fulcrumed adjacent to and at the sides of said conveyer adapted to be simultaneously operated by the movements of said conveyer

and a hopper provided with a chute having a gate connected with said levers to be operated thereby.

7. In a device of the type described, a conveyer provided with a plurality of conveying elements or buckets, a lever fulcrumed adjacent said conveyer and a hopper provided with a chute having a gate connected with said lever to be operated thereby, said lever having a cam surface to be engaged by said conveyer and provided with one or more adjustments for varying the position of said cam face for predeterminedly varying the time of the opening of said gate or the closing thereof.

8. In a device of the type described, a chute having end walls, a gate pivotally connected with said walls, a conveyer, a lever having a cam face provided with anti wear means, such as leather arranged in the path of said conveyer and connected with said gate for operating the same, said conveyer having a plurality of spaced members to coöperate with said lever for periodically actuating the same to open said gate.

9. In a device of the type described, a chute having end walls, a U shaped gate having its arms pivotally connected with said walls, a conveyer, levers having cam faces arranged in the path of said conveyer and connected with said gate for operating the same, said conveyer having a plurality of spaced members to coöperate with said lever for periodically actuating the same to open said gate, and buckets arranged between said members to be positioned beneath said chute during the opening and closing movements of said gate whereby the same may be automatically loaded.

10. In a device of the type described, a chute, a gate pivotally connected therewith, a conveyer comprising a plurality of spaced members and conveying elements arranged between them and adapted to be positioned beneath said chute during the opening and closing movements of said gate, and a lever connected with said gate and provided with a cam face presenting means to effect a gradual opening movement of said gate and abrupt closing thereof and arranged in the path of said spaced conveyer to be operated thereby.

11. In a device of the type described, a chute provided with a gate closing device, a conveyer, lever means having cam surfaces adapted to be actuated by a conveyer member for predeterminedly actuating said lever and to open and maintain said gate opened for a predetermined time, and means for adjusting the position of said cam surfaces relative to said conveyer member for varying the opening and closing movements of said gate.

12. In a device of the type described, conveyer means, a hopper having a chute provided with an oscillatory gate for opening and closing the same, and connected mech-

- anism arranged in the path of said conveyer means, for opening and closing said gate and also for varying the time of opening and closing.
- 5 13. In a device of the type described, a loading device provided with a chute and an oscillatory gate for opening and closing said chute, said gate being fulcrumed upon said chute and having a closing member adapted 10 to slide across the end of the chute and presenting an operating or material arresting face arranged eccentrically relative to the fulcrum of said gate.
14. In a device of the type described, a 15 loading device provided with a chute and an oscillatory gate pivoted thereto at one side of the center line of said chute, whereby the moment force acting to effect movement in one direction is greater than in the other.
- 20 15. In a device of the type described a hopper provided with a forwardly extending inclined chute 3, an oscillatory gate 5 having angular arms 5^a pivotally connected with said chute in rear of the center line thereof 25 and means adapted to be actuated by a device to be loaded for controlling said gate.
16. In a device of the type described, a 30 hopper provided with an inclined chute and an oscillatory gate pivotally connected with said chute in rear of the center line thereof, said gate having a material arresting or releasing surface arranged eccentrically relative to the pivotal support of said gate, the front portions of which are at greater distances 35 from said support than the rear or bottom portions thereof.
17. In a device of the type described, a 40 hopper provided with an inclined chute, an oscillatory gate 5 having angular arms 5^a pivotally connected with said chute in rear of the center line thereof, and means adapted to be actuated by a device to be loaded for operating or controlling said gate, said gate having a material arresting or releasing surface 45 arranged eccentrically relative to the pivotal support of said gate, the front portions of which are at greater distances from

said support than the rear or bottom portions thereof.

18. In a device of the type described, a 50 hopper provided with a chute, an oscillatory gate therefor having a closing member arranged eccentrically relatively to the end of said chute, a conveyer and means intermediate the same and said gate for controlling the 55 opening and closing movements of the latter.

19. In a device of the type described, a 60 hopper provided with a chute, an oscillatory gate therefor, a conveyer, and means intermediate the same and said gate for controlling the opening and closing movements of the latter, said means comprising lever means connected with said gate and arranged in the path of said conveyer and said conveyer having a plurality of long pins 22 and short pins 65 23, alternately arranged with said long pins, conveying elements carried by said short pins to permit free swinging movement thereof between said long pins, said long pins extending across the conveyer and adapted to effect 70 movement of said lever means for operating said gate for successively loading said conveying elements, and said lever means having provision for adjustment for varying the position thereof relative to said conveyer 75 thereby to vary or regulate the opening and closing movements of said gate.

20. In a device of the type described, a 80 hopper provided with an inclined chute, a gate pivoted to the sides thereof, a conveyer, an upright at the side of said conveyer, and a lever pivotally connected to the head of said upright and also connected by an adjustable link with said gate, said lever having a cam surface arranged in the path of said conveyer 85 to be operated thereby for opening and closing said gate.

In testimony whereof, I have signed my name to this specification, in the presence of two subscribing witnesses.

JOHN L. WILSON.
